CLAIM

We claim the ornamental design for a cube pattern, as shown and described.

DESCRIPTION

FIG. 1 is a plan view of a jacket including a cube pattern on a portion thereof;

FIG. 2 is a plan view of a sleeping bag including the cube pattern on a portion thereof;

FIG. 3 is a perspective view of the cube pattern;

FIG. 4 is a plan view of the cube pattern;

FIG. 5 is a front elevation view of the cube pattern, the rear elevation view being a mirror image of the front elevation view; and,

FIG. 6 is a right side elevation view of the cube pattern, the left side elevation view being an identical image of the right side elevation view.

The broken lines shown in the drawings depict environment and form no part of the claimed design.

1 Claim, 4 Drawing Sheets
